DAVID HALLOCK, OF NEW YORK, N. Y.

WEIGHING-SCALE.

SPECIFICATION forming part of Letters Patent No. 325,534, dated September 1, 1885.

Application filed May 4, 1885. (No model.)

To all whom it may concern:

Be it known that I, DAVID HALLOCK, a citizen of the United States, and a resident of New York city, New York, have invented certain 5 Improvements in Weighing-Scales, of which the following is a specification.

My invention consists of certain improvements in the construction of weighing-scales, more particularly of that class in which an 10 oscillating indicator is used.

In the accompanying drawings, Figure 1 is a side view of a scale adapted for postal or letter-weighing purposes and embodying my invention. Fig. 2 is a longitudinal section of the same. Fig. 3 is a transverse section on the line 1 2, Fig. 1. Fig. 4 is a perspective view in section of the jack and its weights and stepped rack. Fig. 5 is a plan view of the scale with the pan removed. Fig. 6 is a perspective view in section of an air-check with its parts detached.

A is the frame, with two upright posts; a a, having at their upper ends bearings for the knife-edges b of the oscillating beam B, the 25 graduated arm of which is preferably of rectangular section and receives the movable weight W. The opposite end of the beam is bifurcated, as shown in the plan view, Fig. 5, and carries the knife-edges d, Figs. 1 and 3, 30 which find bearings in and support the movable jack D, carrying the pan or receptacle to receive the articles to be weighed. This jack is in the form of a yoke, as shown in Fig. 3, and carries a central downwardly-projecting stem, d', connected at its lower end by a guide-rod or link, x, to lugs y on the fixed portion of the frame. The yoke or jack D passes through slots a' in the box-like portion A' of the frame, and the latter on opposite sides of 35 this yoke forms a support for the weights. In the drawings the upper face of the support has a series of steps, s, one slightly above the other. When the jack is in its lowest position, the opposite ends of all the weights E 40 will rest upon the support, but when the jack is raised to its highest position these weights E will all be raised clear of the support. In other words, when the scale is balanced the pan will be carrying all the weights, but as 45 soon as the pan descends when an article is placed therein the jack being connected to that end of the bearing will descend with the

pan and relieve itself of the weights E successively, according to the weight of the article placed in the pan. This action is the reverse of that of the scale shown in the patent granted to me February 3, 1885, No. 311,745, and in which the weights are successively picked up as the pan descends. If desired, the face of the jack D may be stepped 60 and the support or rack A' have a plain face with the same effect.

Over the tops of the weights is a hood or guide, F, which is provided on its opposite inner sides with tapering ribs f to guide the 65 weights. The hood is also tapered on the inside and the weights are correspondingly tapered on all sides, as shown in Figs. 2 and 3, so that when the weights descend there will be no frictional contact between the weights 70 and hood.

In the construction shown in the drawings the graduated arm of the scale-beam itself acts as an indicator, having its point adapted to act in connection with the graduated scale 75 R, Figs. 1 and 2, mounted on the end of an arm, r, of the frame.

The scale shown in the drawings is adapted more particularly for postal use, and for this purpose this indicator-scale R is shown as 80 having four divisions for the half-ounces for weighing letters, while the beam is graduated into two-ounce spaces, so that in weighing letters or packages of two ounces or less no movement of the weight W is needed, while 85 for over two ounces and less than four the weight W is moved one space from the pivoting point, and so on.

When the scale is balanced—that is to say, when the jack is in the raised position, supporting all the weights E clear of the rack—the indicator will point to zero; but the moment a letter, for instance, is placed in the pan the latter will descend, and if the letter weigh but a fractional part of half an ounce the pan 95 will descend until the first weight E comes into contact with the corresponding part of the rack, when the beam will point to the first or half-ounce division of the scale and so indicate the weight on which postage is payable 100 on the letter.

When an article weighing over half an ounce, but not more than one ounce, is placed on the pan the latter will descend and with it the jack,

which will move away from the first weight and descend until the second weight comes into contact with the rack, as shown in Fig. 3, when the beam will point to the ounce-mark 5 on the indicator, as shown in Fig. 1. So for any other weights of letters or other articles the beam will turn always to one or other of the full-unit divisions on the indicator, thus showing the weight on which the rate of postage is payable, even if the letter or other article weigh a fraction less, but nevertheless demands that rate of postage. In other words, owing to the automatic weights and the balancing of the scale, as described, the jack will 15 be relieved of none of the weights until it passes the first unit-mark, and consequently fractional parts will be indicated as full units.

Multiples of the smaller units on the indicator-scale R are found on the graduations of 20 the beam, and by moving the weight W thereon heavier articles may be weighed just as readily, and in conjunction with the automatic weights and indicator.

An air-check is combined with the scale to 25 prevent undue oscillation of the indicator and to bring the latter to a state of rest immediately after an article to be weighed has been thrown onto the pan of the scale. In the construction herein illustrated it consists of a 30 box, H, carried by the jack D, and having adapted thereto one or more diaphragms, J, which in the present instance are shown as resting on a cup or support, I, on the top of the fixed portion of the frame (in this case the hood F) when the frame is at rest. These diaphragms are preferably cut out of sheet metal, and if there are more than one they are separated a slight distance from each other by suitable projections, j, which may be teats 35 stamped up from the diaphragms themselves. In Figs. 2 and 3 I have shown three of these diaphragms as being a desirable number. The diaphragms fit comparatively closely within the walls of the box H so as to leave but small 40 outlet or inlet for the passage of air around their margins when the scale-beam is moved.

The diaphragms J may, if desired, be connected to their support I; but in all cases it should be a loose connection, so that they will 45 be free to have a lateral motion to accommodate themselves under all circumstances to the movements of the box, for otherwise the closeness of the peripheries of the diaphragms to the walls of the box is such that if they were secured 50 to their support the parts would jam and prevent proper action, while on the other hand in an air-check of this character this closeness of the parts is necessary to give the proper action.

If desired, the closed top of the box H may be provided with a small perforation or outlet, h, to ease the movements of the parts.

I do not wish to confine myself to the precise construction of air-check above described, as other forms and arrangements may be used 65 with similar effect. Thus the box H may be applied to the lower end of the stem d' of the jack instead of being carried by the upper end of the jack, and the loose diaphragms J in this case will be carried by a support mounted on 70 a transverse plate secured to the frame beneath the box H.

I prefer in all cases to use more than one diaphragm, as I find this to be more effective in its action, the use of two diaphragms, for 75 instance, giving almost double the retarding effect of a single diaphragm.

I claim as my invention—

1. A weighing-scale having an indicator provided with an air-check, consisting of a box 80 and a loose diaphragm or diaphragms therein, substantially as described.

2. The combination of the oscillating beam of a weighing-scale and a box controlled thereby, with a support and loose diaphragms 85 adapted to said box and normally resting on the support, as set forth.

3. The combination of the beam of a weighing-scale and pan carried thereby, with a jack connected to the pan end of the beam, a series 90 of automatic weights normally carried by the jack, and a support to relieve the jack of the weights successively as the pan descends, substantially as specified.

4. The combination of the beam and indicator-scale of a weighing-scale, with a jack carried by the pan end of the beam, a series 95 of automatic weights normally carried by the jack, and a support for the weights when relieved from the jack; the beam being balanced, substantially as described, whereby fractional parts will be indicated as full units.

5. A weighing-scale having a graduated beam provided with a movable weight, and an indicator - scale and a series of automatic 105 weights, the latter indicating the small units, while the graduations on the beam are multiples of the small units, as set forth.

In testimony whereof I have signed my name to this specification in the presence of two sub- 110 scribing witnesses.

DAVID HALLOCK.
